UNITED STATES PATENT OFFICE.

LOUISA P. BUNNELL AND WILLIAM NICHOLS, OF TOLEDO, OHIO, ASSIGNORS
OF ONE-THIRD TO GEORGE K. DETWILER, OF TOLEDO, OHIO.

SELF-THREADING NEEDLE.

SPECIFICATION forming part of Letters Patent No. 735,458, dated August 4, 1903.

Application filed November 3, 1902. Serial No. 129,943. (No model.)

To all whom it may concern:

Be it known that we, LOUISA P. BUNNELL and WILLIAM NICHOLS, citizens of the United States, residing at Toledo, in the county of Lucas and State of Ohio, have invented certain new and useful Improvements in Self-Threading Needles; and we do declare the following to be a full, clear, and exact description of the invention, such as will enable others skilled in the art to which it appertains to make and use the same, reference being had to the accompanying drawings, and to the letters of reference marked thereon, which form a part of this specification.

15 In the patent granted to us for self-threading needles February 13, 1900, No. 643,398, we describe and claim a needle having a cut at a right angle to the axis thereof and coinciding with the bottom of the eye of the needle, the 20 cut having a flaring mouth with upper and lower rounded corners. While this needle in practice is found to serve its purpose admirably, experience has shown that the angles of the portions of the needle adjacent to the 25 transverse cut tend to catch slightly upon the thread and fibers of the fabric as the needle is pushed into and withdrawn therefrom.

Our invention relates to and its object is to provide means for overcoming the objections 30 and difficulties here indicated.

A further object of our invention is to reduce to a minimum the friction of the needle in the fabric and to so form the needle at the mouth of the transverse cut above referred 35 to that the angles thereof shall not when the needle is in motion touch the fabric at all.

We attain the objects above referred to by means of the devices and arrangement of parts hereinafter described, and shown and 40 illustrated in the accompanying drawings, in which—

Figure 1 a side elevation of a sewing-machine needle embodying our improvement, and Fig. 2 a front elevation of the same.

45 Like letters of reference indicate like parts throughout the drawings.

In the drawings, *a* is the shank, *b* the shaft, and *c* the eye, of the needle. Extending upwardly from both sides of the eye are formed

the usual long and short grooves in the shaft 50 of the needle.

d is a transverse cut or opening leading from the side of the needle into the eye *c*. The longitudinal axis of the needle is at a right angle and perpendicular to this cut. The cut *d* leads 55 to and coincides with the end of the eye next to the point and is barely of sufficient width vertically to permit the passage of the coarsest thread designed to be used with the needle. The front of the depending lip formed by the 60 eye and the transverse cut, together with the ledge formed by said cut at the bottom of the eye, are concaved inwardly beyond the general exterior surface of the needle, as at *e*, Fig. 1. These two portions are likewise concaved inwardly and equally at their two sides, as shown at *f*, Fig. 2, that portion of the needle 65 back of the inner vertical wall of the eye retaining its usual nearly semicylindrical shape.

The operation of our device is as follows: 70 The needle being properly secured in place in the sewing-machine, the horizontal thread is pressed laterally against the front of the needle at the concaved portions *e f*. Now a very slight vertical movement of the needle or 75 of the thread will cause the thread, guided by the inwardly-curved exterior surfaces of the needle, to slip sidewise into the cut *d* and into the eye at the extreme bottom of the eye. The upward pull of the tension devices of the 80 sewing-machine and the normal position of the thread now hold the thread above the cut *d*, so that the thread does not escape through the cut.

The advantages of the construction here described are, first, the needle may be threaded much more easily than heretofore; second, the outer angles of the transverse cut do not come in contact with the fibers and threads of the fabric sewed upon, since these angles are entirely within the curved plane of the general surface of the needle, and, third, the needle moves within the fabric with less resistance than heretofore. 90

Having described our invention, what we 95 claim, and desire to secure by Letters Patent, is—

The needle herein described, the same hav-

ing a cut at a right angle to the perpendicular axis of the needle, and coinciding with the bottom of the eye, the dependent lip and the ledge formed by the eye and said transverse cut having their fronts and both sides concaved inwardly within the curved plane of the general surface of the needle, substantially as and for the purpose specified.

In testimony whereof we affix our signatures in presence of two witnesses.

LOUISA P. BUNNELL.
WILLIAM NICHOLS.
